(57) **CLAIM**

The ornamental design for a sterilization device, as shown and described.

DESCRIPTION

FIG. 1 is a front elevation view of a first sterilization device of the present invention;

FIG. 2 is a rear elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front perspective view thereof; and

FIG. 8 is a rear perspective view thereof;

FIG. 9 is a front elevation view of a second sterilization device of the present invention;

FIG. 10 is a rear elevation view thereof;

FIG. 11 is a left-side elevation view thereof;

FIG. 12 is a right-side elevation view thereof;

FIG. 13 is a top plan view thereof;

FIG. 14 is a bottom plan view thereof;

FIG. 15 is a front perspective view thereof; and,

FIG. 16 is a rear perspective view thereof.

The broken lines shown in the drawings are for the purpose of illustrating portions of the sterilization device that form no part of the claimed design. The broken lines form no part of the claimed design.

1 Claim, 16 Drawing Sheets
